CLAIM

The ornamental design for a ceiling fan, as shown and described.

DESCRIPTION

FIG. 1 is a top perspective view of a ceiling fan showing my new design;

FIG. 2 is a bottom perspective view of the ceiling fan of FIG. 1;

FIG. 3 is a top view of the ceiling fan of FIG. 1;

FIG. 4 is a bottom view of the ceiling fan of FIG. 1;

FIG. 5 is a front view of the ceiling fan of FIG. 1;

FIG. 6 is a left side view of the ceiling fan of FIG. 1;

FIG. 7 is a rear view of the ceiling fan of FIG. 1; and,

FIG. 8 is a right side view of the ceiling fan of FIG. 1.

Portions of the ceiling fan shown in broken lines form no part of the claimed design.

The ceiling fan blade is shown with a symbolic break in its length. The appearance of any portion of the ceiling fan blade between the break lines forms no part of the claimed design.

1 Claim, 8 Drawing Sheets
